UNITED STATES PATENT OFFICE.

JOHN WESLEY FERGUSON, OF BLOOMFIELD, NEW JERSEY.

SAD-IRON.

No. 826,415.

Specification of Letters Patent.

Patented July 17, 1906.

Application filed August 29, 1905. Serial No. 276,265.

To all whom it may concern:

Be it known that I, JOHN WESLEY FERGUSON, a citizen of the United States of America, residing at Bloomfield, in the county of Essex and State of New Jersey, have invented 5 new and useful Improvements in Sad-Irons, of which the following is a specification.

My invention relates to sad-irons of that 10 class in which charcoal is used for fuel; and its primary object is to provide a novel and highly-useful device of this character wherein in the top side of the body of the iron is closed, except for a feed-opening, and has 15 formed integrally therewith two handle-supporting standards and to provide a combined handle and lid which may be readily and quickly applied and removed. The lid serves to close the feed-opening.

20 A further object of the invention is to provide a device of the character stated which has but few parts of simple construction and which may be manufactured and sold at a comparatively small cost.

25 The invention consists in the construction, combination, and arrangement of parts hereinafter fully described, claimed, and illustrated in the accompanying drawings, wherein—

30 Figure 1 is a vertical longitudinal sectional view of a sad-iron constructed in accordance with my invention. Fig. 2 is a view in rear elevation thereof. Fig. 3 is a top plan view thereof, the combined handle and lid being 35 removed. Fig. 4 is a transverse sectional view thereof, and Fig. 5 is a detail perspective view of the combined handle and lid.

Referring to the drawings by reference-numerals, 1 designates the body of the sad- 40 iron, which, as usual, is hollow and which is of the usual form. The forward end of the body is provided with a flue 2, the same being formed integrally therewith, and the rear wall thereof is provided with a draft-opening 45 3, said draft-opening being controlled by means of a door pivotally hung upon the rear wall of the body. On the interior of the body is an approximately U-shaped flange 4, said flange curving inwardly and down- 50 wardly to provide a flue 5, which extends clear across the rear wall of the body and along the side walls thereof and terminates at a point adjacent the forward end of the body. The flange 4 terminates at a short distance 55 from the inner face of the base of the body 1

to provide a passage 6, through which may emerge the draft from the flue 5 directly under and on three sides of the fuel, whereby to provide for a ready combustion of the charcoal within the iron. The rear wall of the 60 body 1 has formed integrally therewith a flange 7, the same curving upwardly to provide an ash-receptacle located directly below the draft-opening 3, whereby any ashes which may come out through the opening 3 65 will be caught by said receptacle and be prevented from falling upon the article being ironed. The top wall of the iron is provided with an opening 8, through which may be fed the charcoal, and about said opening with a 70 reduced portion providing a seat 9. Rising vertically from the rear wall of the iron and from the top wall thereof in rear of the flue 2 are handle-supporting standards 10, said standards having their upper ends provided 75 with alining openings 11. A lid 12 is adapted to be positioned on the seat 9 to fully close the opening 8, and rising vertically from the ends of the lid are arms 13, which have secured to their upper ends a handle of wood 80 14. The ends of the handle 14 are recessed to receive the upper ends of the standards 10, and said handle is provided with a longitudinally-extending opening 15 to permit of the application of a pin 16 to secure the handle 85 and lid in applied position.

It is apparent that the lid 12 may be easily and quickly removed to clear the opening 8 when it is desired to replenish the supply of charcoal and that the same may be quickly 90 and readily replaced and secured in applied position. The engagement of the edges of the lid 12 with the vertical edges of the seat 9 prevents the handle and lid from turning upon the pin 16 and also permits of the opening 8 being so closed as to prevent the escape of the products of combustion therethrough. The arms 13 of the lid 12 lie in engagement with the inner faces of the standards 10, and thereby form no obstruction and do not detract from the appearance of the iron. 95

Changes in the form, proportions, and minor details of construction may be made within the scope of the invention without departing from the spirit or sacrificing any of 100 the advantages thereof.

Having fully described and illustrated my invention, what I claim is—

105 A sad-iron comprising a body having its forward end formed to provide a flue and 110

having an opening in its top, the top about the opening being reduced to provide a seat, a standard rising vertically from the rear wall of the body, another standard rising vertically from the top in rear of the flue, a lid adapted to be positioned on the seat and provided with arms rising vertically from the ends thereof, a handle secured to the arms of

the lid, and a pin passing through the standards and arms.

In testimony whereof I affix my signature in presence of two witnesses.

JOHN WESLEY FERGUSON.
